US0D1102103S

(12) United States Design Patent (10) Patent No.: US D1,102,103 S
(45) Date of Patent: * Nov. 18, 2025

(54) SHOE

(71) Applicant: adidas AG, Herzogenaurach (DE)

(72) Inventor: Luke Lowrey, Erlangen (DE)

(73) Assignee: adidas AG, Herzogenaurach (DE)

() Term: 15 Years

(21) Appl. No.: 29/856,513

(22) Filed: Oct. 14, 2022

Related U.S. Application Data

(63) Continuation of application No. 29/730,928, filed on Apr. 9, 2020, now Pat. No. Des. 966,678.

(57) CLAIM

The ornamental design for a shoe as shown and described.

DESCRIPTION

FIG. 1 is a left side view of a shoe showing the claimed design;

FIG. 2 is a right side view thereof; and,

FIG. 3 is a rear view thereof.

The broken lines in the figures show portions of the shoe that form no part of the claimed design.
